MULTI-BAND PORTABLE RADIO

Richard Culbertson, Manlius, and Cornelius W. Christie,
Fulton, N.Y., assignors to General Electric Company

Filed Feb. 16, 1972, Ser. No. 226,996

Term of patent 14 years

Int. Cl. D14—03

U.S. Cl. D56—4 B

Fig. 1

Fig. 2

Fig. 3

Fig. 4

Fig. 5

Fig. 6

FIG. 1 is a front elevational view of a multi-band portable radio, showing our new design;

FIG. 2 is a top plan view;

FIG. 3 is a right side elevational view;

FIG. 4 is a left side elevational view;

FIG. 5 is a rear elevational view; and

FIG. 6 is a bottom plan view thereof.

We claim:

The ornamental design for a multi-band portable radio, substantially as shown.
